MAGNETRON

Karl Fritz, Berlin, Germany, assignor to Tele-funken Gesellschaft für Drahtlose Telegraphie m. b. H., Berlin, Germany, a corporation of Germany

Application November 12, 1936, Serial No. 110,439
In Germany November 5, 1935

10 Claims. (Cl. 250—27.5)

The present invention relates to electron discharge devices, more particularly magnetrons with several anode segments, as well as circuit arrangements for producing high power when making use of these new tubes wherein reactive effects between the electrodes carrying alternating current (anode reaction) are avoided.

The power of a short-wave tube is limited essentially for two reasons: In the first place, the source provided for electron emission (cathode) may not be able to furnish a sufficiently large emission current and in the second place, the electrodes provided for the reception of emitted electrons may not be capable of absorbing the emission current coming from the cathode without the danger of destruction.

The cathode question is no longer of importance since the prior art has succeeded building high-emitting cathodes or so-called large-surface cathodes.

The principal difficulties are encountered in anode construction. The diameters of the anodes may not be increased beyond certain dimensions in practice for otherwise unreasonably high acceleration potentials must be applied for insuring a short transit time of the electrons. Moreover, the dimensions of the anodes in direction of the axis of electrode system cannot be chosen at will since an increase in the anode surface invariably results, with constant electrode distance, in an increase of the internal tube capacities which limits the range of the production of very short waves. In magnetron tubes an axial length as short as possible is desirable for the reason that the strong magnetic field extending through the discharge space must be homogeneous, and hence a considerable expenditure of magnet energizing power is required which must be increased with longer axial length. If the frontal electrodes (anodes) are increased in size for more favorable cooling conditions, the constructional length of the tube is increased considerably in axial direction and therewith the magnetic resistance of the path to be traversed (air gap). Besides, the endeavor to draw the emission current to the frontal electrodes is only partly successful. Not all electrons thrown off by cathode move in planes at right angle to cathode, many of these planes form in fact angles deviating from the right angle to the axis of system. These latter electrons move in a spiral line under the influence of the electric transverse field, whose axis is inclined to the axis of system, and they reach finally, even if not after the first revolution, the current-carrying electrodes. The influence of the electric trans-

verse field on the electrodes varies greatly. It is a maximum at the ends of the discharge system and decreases strongly towards the center. Accordingly, the electrons emitted at the extremities of cathode pass directly to any end electrodes provided and thus do not at all contribute to the generation of oscillations. On the other hand, the electrons emitted in the center of cathode are not influenced at all for practical purposes by the electric transverse field.

The raising of the efficiency in the usual magnetrons is limited for the reason that excessive alternating potentials between the oscillation electrodes interfere with an orderly course of the electrons so that the excitation of electrons is decreased. This detrimental "anode reaction" appears the more pronounced the greater the power output.

It is the principal object of my invention to provide a magnetron of increased power output and efficiency.

The novel features which I believe to be characteristic of my invention are set forth with particularity in the appended claims, but the invention itself will best be understood by reference to the following description taken in connection with the accompanying drawings in which Figures 1a, b and c, are diagrammatic transverse sections of electron discharge tubes embodying my invention, Figures 2 to 4 inclusive are modifications of electron discharge tubes embodying my invention, Figures 5 and 6 are circuit arrangements using tubes embodying my invention, Figures 7a, 7b show further modifications of electron discharge tubes embodying my invention, Figures 8, 9, 10a and 10b show other modifications and circuit arrangements embodying tubes made according to my invention.

By means of the present invention the problem of power increase in a tube is solved in a fully novel manner:

The electrodes carrying alternating current are not affected by the waste heat produced through the impingement of the electrons. For this purpose a pick-up or collecting electrode is provided for the electrons having the same distance from all points of the cathode with the result that its action extends uniformly over all electrons coming from cathode.

This new electrode shows pronounced screen electrode properties. It remains electrically neutral like a screen grid in a standard tube, in other words it carries no alternating potential with respect to cathode, in particular no alternating potential of the magnitude or frequency

of the oscillations produced. If it is impressed with a sufficiently high positive operating biasing potential, the resulting potential becomes within the oscillation electrode cylinder approximately cylindro-symmetrical, disregarding the necessary electric transverse fields. It also happens in practice that with high oscillating alternating potentials the oscillation electrodes (anodes) are operated at times in over-charged condition in the manner that the momentary potential of an oscillation electrode or electrode group assumes a negative value during a half-period with respect to cathode.

The electron tube according to the invention, in particular a magnetron tube, with several electrodes (anodes) enclosing the cathode is characterized in that the electrode group, producing the oscillations and consisting of the current-carrying electrodes and the cathode, is enclosed by a single electrode, or several interconnected, electrodes (screen or pick-up electrodes).

An oscillating system may be used in the magnetron as long as it has perforated or slotted electrodes thus presenting the possibility that the electrons may impinge on the neutral pick-up electrode. The surface of the pick-up electrode is provided with cooling fins or the like for increasing heat radiation (natural cooling). The pick-up electrode may also be provided with arrangements for artificial cooling by means of a liquid or gaseous medium. A particularly advantageous construction results if the pick-up electrode is developed as a hollow cylinder, the other discharge electrodes being grouped concentrically within this cylinder. The pick-up electrodes form in this case at the same time a partial closure of the discharge space. The ends of the metallic cylinder are closed gas-tight with insulating members, particularly of ceramic material. These closing pieces are at the same time suitably made to participate in the support and centering of electrodes. In the case of use of this tube as a magnetron the electrodes are suitably made of non-magnetic material, thus preserving the homogeneity of the lines of force flux within the discharge space.

The novel tubes are to find their use principally in magnetron circuit arrangements for the purpose of insuring high power at short waves. As stated previously, the entire power loss (heat) is to be absorbed by the electrically neutral pick-up electrodes, while the oscillation energy is taken from the electrodes carrying alternating current only (anodes) and being freed of their load. For the reason that no alternating potential, at least none of the generated frequency, appears at the neutral pick-up electrode or electrodes, they can be developed in any desired manner and in particular can be grounded during operation. Complicated arrangements for insuring high ohmic or alternating resistances, such as would be required in water-cooled alternating current-carrying electrodes, are entirely superfluous in the present case, particularly when the pick-up electrode itself, or the corresponding pole of the biasing potential source is impressed with earth potential, similar to the arrangement usual in X-ray tubes.

In many cases where a reduction of the power loss at the oscillation electrode appears to be advisable, for instance in oscillations with magnetic fields of first magnitude where the over-all efficiency is poor, it may prove advantageous to use perforated screen electrodes and to dispose behind the screen electrodes having maximum

positive potential the pick-up electrode proper with an average positive biasing potential that will retard the electrons and absorb the same with lower potential or velocity. Of equal importance as a suitable assembly of the discharge system is the choice of operating conditions. It is only the coordination of both that insures ideal separation of power loss and oscillation power, in other words their distribution over different types of electrodes. The operating conditions, that is electrode biasing potentials and magnetic field must be chosen in the manner that an oscillation generation or amplification with respect to the oscillation electrodes as well as a catching of the electrons, which have already contributed to the oscillation generation, is insured by the pick-up electrodes. Experiments have shown that with correctly chosen operating conditions and corresponding tube construction no oscillation energy may be detected at the pick-up electrodes even if the latter are sub-divided and actually even if they are tuned to the produced frequency by means of suitable supplementary circuit elements. Even in the last-named case of resonance tuning in the pick-up electrode circuit no reactive influences of any kind are perceptible with respect to the interiorly disposed oscillation system for the electrons and in irregular sequence. The oscillation electrodes must, looking in a direction parallel to the axis of system, closely hug the paths of the revolving electrons, that is must have a course parallel to the latter so that the electrodes are hit to the least possible extent by the electrons. In view of above, preference will be given to oscillation electrodes with a cross-section in the form of a circular arc.

By means of the introduction of the positive screen electrode, under the assumption of a sufficient gain reciprocal through the perforated oscillation electrodes, the electric acceleration direct current field may be chosen independent of the control alternating current fields in cylindro-symmetrical arrangement. This independence in the formation of the fields may be utilized to special advantage in a two-part oscillating system in the manner that the two oscillation electrodes are not disposed on a circle coaxial to the pick-up electrode, but are given a greater radius of curvature so that they are disposed in an ellipse-like curve at the center of which is located the cathode. By this arrangement the influence of the electric alternating current control fields on the cathode for the purpose of a sorting-out electron correct in phase (cathode separation) is increased, a possibility which may be of importance in particular in oscillations of the first order.

The alternating current carrying, positively biased oscillation electrode (anodes) will not absorb any direct current for all practical purposes especially in case of a grid-like construction. The discharge path co-ordinated thereto has accordingly a very high resistance so that a control potential source connected in series therewith receives no or hardly any load. It is even possible to arrive at a condition where a negative direct current appears in the circuit of the oscillation electrodes and that is when the anodes have the property to throw off secondary electrons. These secondary electrons may likewise be put to good use.

Under normal conditions the fast primary electrons are accelerated by the oscillation electrode that is positive at the moment of exit and

are curved or deflected by the magnetic field. They then travel parallel to the short side of an oscillation electrode whose momentary potential is negative (leaving the biasing potential out of consideration). Electron m_1 in traveling by, attracts through its influence a positive charge towards the electrode A_1 , Fig. 1a giving a negative resistance effect.

If it should happen that a primary electron reaches an oscillation electrode, it will land on an electrode whose momentary potential happens to be positive. This would have the result that additional further positive charge would be drawn to the positive electrode (positive resistance). In other words, the electron lands at the wrong time with respect to phase and interferes with the excitation of oscillations. Fig. 1b indicates this case under the assumption that oscillation electrode A_1 is in no way adapted to emit secondary electrons. The circuit arrangement is completed in Fig. 1b. The tube vessel R contains the cathode K and the positively biased pick-up or screen electrode N . The oscillating circuit is formed of inductance L and capacity C . A magnetic coil M induces a magnetic field between cathode and anode parallel to the cathode.

Fig. 1c illustrates a case by way of example where even a landing electron may still contribute to the excitation of oscillations. Let m_1 be the primary electron that flies towards positive oscillation electrode A_1 with the high velocity v_1 but wrong in phase. It impinges thereon and releases a number of secondary electrons m_2 with lesser speeds v_2 . In given cases the primary electron itself is reflected (m_1) by tangential incidence. This results in that a negative charge is drawn to positive electrode A_1 and the oscillation excitation is thus supported correct in phase. It is preferable for this reason in tubes according to invention to render the oscillation electrodes capable of secondary emission by means of suitable treatment of the surfaces or suitable material.

Figs. 2-3 show by way of example tube constructions or circuit arrangements in accordance with invention for insuring high power output, particularly modulated oscillation output, in schematic manner.

Fig. 2 shows a section transverse to the axis of a concentrically arranged electrode system. Cathode K forms at the same time the axis of the discharge system. On a circle disposed coaxially with the cathode are arranged four anode segments A_1 , A_2 , A_3 and A_4 , of equal size and displaced cyclically by 90° . These anodes or oscillation electrodes may be connected together in the manner known in prior art and with a resonance system. Behind these oscillation electrodes are disposed, likewise on a circle co-axial with the cathode, four further pick-up or collecting electrodes N_1 , N_2 , N_3 , N_4 which cover the corresponding slots between oscillation electrodes A . The pick-up electrodes are suitably directly connected electrically to each other by short-circuit connections K_v . The entire discharge system is enclosed in a hermetically sealed vessel R .

The phenomena inside the tube may be explained in this manner: the pick-up electrodes N furnish merely the electric direct current field required for acceleration of electrons while the oscillation electrodes (anodes) are coupled to the oscillating action of the electrons, for example capacitatively. The alternating potentials excited at the oscillation electrodes by influence of

the electrons that pass by, retroactively control the electron course.

In Fig. 3 are indicated the approximate paths of the electrons without these theoretical data limiting in any manner the mode of operation of the invention. One electron shall be selected out of the multitude. Its path shall be studied. It travels from the cathode toward oscillation electrode A_1 . The difference between the maximum diameter of the electron path and anode radius is d_1 . It turns back, travels to the vicinity of cathode and, at the proper moment, towards anode A_2 . The approach to anode A_2 is closer. The distance from anode A_2 is d_2 . The action repeats itself until the radius of the path, say after passage past anode A_4 , becomes so great under the influence of pick-up electrode N , that the electron leaves the oscillation space and flies to electron N as indicated by the curved arrow. In magnetrons with two oscillation electrodes it is preferable to construct these electrodes in perforated form, perhaps grid-like, so that the influence of electrode N is sufficiently strong.

Fig. 4 shows a tube in transverse section, the foraminous oscillation electrodes A_1' , A_2' , A_3' and A_4' having mesh- or grid-like form. Optimum electric conditions are encountered if they consist of grid wires running at right angles to the cathode. Pick-up electrode N consists of a metallic cylinder N closed electrically up to the front sides and equipped with cooling ribs or fins Z . In order to vary the intensity of the field produced by coil M , the source of supply V may be connected in series with the rheostat R_1 and the coil M . The intensity of the field determines the radius of the path of the electrons around the cathode.

Fig. 5 shows the principle of a master-controlled amplifier tube provided with a multiple system. Both oscillating systems are enclosed by a pick-up electrode N . K is the cathode. J_1 and J_2 are the electrodes of the inner system connected with an oscillating circuit S_t which for instance is excited by a control oscillator O . The amplified oscillation power is taken from perforated outer electrodes A_1'' , A_2'' through an oscillating circuit H and brought to a receiver V . The case of course may exist where the inner system J_1 , J_2 is excited to independent oscillations and where system A_1'' , A_2'' is controlled by entrainment. Both oscillation systems are enclosed by the electrically neutral pick-up electrode N which absorbs as completely as possible the electrons after their work and thus lessens the anode retraction.

Fig. 6 shows a modulation circuit arrangement where the modulation of the oscillations produced in the tube is accomplished by means of the pick-up electrodes. The oscillation system, consisting of electrodes A_1 , A_2 , A_3 , and A_4 and resonance circuit H , operates in a self-excited circuit arrangement. The two parts N_1' and N_2' of pick-up electrode are connected through capacities C_h inside or outside the tube. These capacities shall be dimensioned so that they present no appreciable resistance for the frequency of the produced oscillations, but offer a considerable resistance for the modulation or regulation potentials. The modulation potentials are impressed on pick-up electrodes N_1' and N_2' in push-pull arrangement by means of a modulation transformer M . The center terminal of the secondary of modulation transformer M is connected with the positive pole of the co-ordinated biasing potential source U_h . Hence, the source of the mod-

ulation oscillations is not connected in series with the discharge path comprising cathodes and pick-up electrode, and cannot be loaded by the low resistance of this path. Cathode K is fed by a heating transformer T. Oscillation electrodes A₁, A₂, A₃ and A₄ are impressed with an average positive biasing potential U_a and pick-up electrodes N with the maximum positive biasing potential U_n with respect to cathode.

10 It is of course also feasible, according to Figs. 7a, 7b, to divide the pick-up electrodes N₁', N₂' not in sections parallel to axis of system, but by one or several sections at right angle to the axis of system and to connect these parts in suitable manner.

15 A tube similar to Fig. 6 is shown in Fig. 8. The difference consists in that the pick-up electrodes N₁' and N₃' are bridged capacitatively by two further, exteriorly disposed pick-up electrodes N₁'' and N₂'' and mutual capacities C_n with respect to the frequency of the produced oscillations. The maximum positive biasing potentials are in this case impressed on external electrodes N₁'', N₂''. If as shown, a modulation by means 20 of electrodes N' is done, it is preferable to impress asymmetrically one of the electrodes or electrode groups with an auxiliary biasing potential, for instance by means of a battery B, for preventing a doubling of the modulation frequency during modulation.

25 Fig. 9 shows a complete modulation circuit arrangement. The four oscillation electrodes A₁, A₂, A₃, A₄ work together with a resonance circuit H in a self-excited arrangement. This oscillation system is enclosed by four perforated "neutral" electrodes N₁', N₂', N₃', N₄' arranged in a circle co-axial to cathode. Each of the two opposite neutral electrodes N₁', and N₃', N₂' and N₄' resp., are interconnected. The modulation 30 potentials are impressed on these two groups in opposite phase. The biasing potential for all the neutral perforated electrodes is approximately the same and positive (U_a'). Behind electrode N' is disposed the pick-up electrode proper N_o'', impressed with an average positive biasing potential U_n'' about of the size of oscillation electrode potential U_a. The electrons are mainly accelerated by the maximum positive potential (U_n') of electrodes N'. After passage through the perforated 35 electrode N' they are retarded by the small potential of electrode N'' and land with smaller speed on pick-up electrode proper N_o''.

40 In Fig. 10a is shown a tube working in co-operation with a poorly radiating oscillation circuit. The mutual capacities of oscillation electrodes A₁ and A₂ form a closed resonance circuit together with inductances L₁ which divide at points C_u in two parallel connected inductances L_a' and L_a'' in the form of semi-cylindrical shells 45 providing a closed housing around the electrodes. The bridging capacities must be large compared to the mutual capacities of oscillation electrodes if they are not to be used for frequency regulation. On outer parts L_a' and L_a'' are formed at 50 points P', P'' potential nodes which carry no alternating potential with respect to earth (cathode). To this point are connected pick-up electrodes N₁' and N₂''. At one of these points the pick-up electrode is impressed with the positive biasing potential and at another point the cathode feed line is introduced in the interior of the discharge system. The pick-up electrodes are connected with the exteriorly disposed oscillation 55 inductances L_a' and L_a'' a great part of the

oscillation circuit participating in the radiation of the waste heat.

5 The principle of the circuit arrangement is indicated in Fig. 10b. A particularly favorable embodiment results when the oscillation circuit is developed in form of a globe. For introduction of the electrode leads, holes must be provided at points p' and C_u.

10 It appears essential to once more emphasize at this point that the oscillation system disposed inside the electrically neutral pick-up electrode (N) may be developed in any desired manner. It may be constructed as a master control system with two built-in electrode systems having different distances from the cathode. It may even consist of a cathode and cylindrical anode, only, assuming that the anode is of grid- or mesh-like form to allow passage of the electrons. Auxiliary electrodes for modulation, regulation, control, etc. may be used in line with all possible and 15 usual schemes for magnetrons and variants. Thus, a modulation with the aid of oscillation electrodes (anodes) in straight or push-pull arrangement is possible or a combined modulation. Nothing prevents the arrangement of disk-like 20 electrodes at the front side of the discharge systems using the same for excitation of oscillations and/or modulation.

25 While I have indicated the preferred embodiments of my invention of which I am now aware 30 and have also indicated only one specific application for which my invention may be employed, it will be apparent that my invention is by no means limited to the exact forms illustrated or the use indicated, but that many variations may be made in the particular structure used and the purpose for which it is employed 35 without departing from the scope of my invention as set forth in the appended claims.

40 I claim:

1. An electron discharge device having an envelope containing a straight thermionic cathode and a plurality of anodes surrounding said cathode, and a collecting electrode outside of said anodes for receiving electrons from said cathode, and means for inducing a stable magnetic field between said cathode and anodes parallel to said cathode. 45

2. An electron discharge device having a straight thermionic cathode and a plurality of anode segments surrounding and parallel to the cathode, a second electrode surrounding said cathode and said anodes for receiving electrons from the cathode and means for inducing a magnetic field between said cathode and anode segments parallel to said cathode. 50

3. An electron discharge device having an envelope containing a straight thermionic cathode and a plurality of anode segments surrounding said cathode, said anode segments being parallel to the cathode and arranged in oppositely disposed pairs at different distances from the cathode, and an electrode surrounding said cathode and anode segments, and means for inducing a magnetic field between said cathode and anode segments parallel to said cathode. 55

4. An electron discharge device having an envelope containing a straight thermionic cathode and a plurality of foraminous anode segments surrounding said cathode and a cylindrical electrode surrounding said cathode and anodes, and means for inducing a magnetic field between said cathode and anode segments. 60

70 5. An electron discharge device having an envelope containing a straight thermionic cath-

ode and a plurality of foraminous anode segments surrounding said cathode and a solid cylindrical electrode surrounding said cathode and anodes and provide with radially extending cooling fins, and means for inducing a magnetic field between said cathode and foraminous anode segments.

6. An electron discharge device having an envelope containing a straight thermionic cathode and a plurality of anodes surrounding said cathode, and a collecting electrode outside of said anodes for receiving electrons from said cathode, and means for inducing a magnetic field between said cathode and anodes parallel to said cathode, and an oscillating circuit in the form of a closed screen housing carrying the collecting electrode at the electrically neutral points on said oscillating circuit.

7. An electron discharge device having an envelope containing a straight thermionic cathode and a plurality of anodes surrounding said cathode, and a collecting electrode of non-ferromagnetic material outside of said anodes for receiving electrons from said cathode, and means for inducing a stable magnetic field between said cathode and anodes parallel to said cathode.

8. An electron discharge device having a straight thermionic cathode and a plurality of

anode segments surrounding said cathode, said anode segments being perforated and enclosed by a solid sheet metal collecting electrode, and means for inducing a magnetic field between said cathode and said anode segments.

9. An electron discharge device having an envelope containing a straight thermionic cathode and a plurality of anodes surrounding said cathode, and a collecting electrode outside of said anodes for receiving electrons from said cathode, and means for inducing a stable magnetic field between said cathode and anodes parallel to said cathode, and means for adjusting the magnetic field so that all of the electrons are received by the collecting electrode.

10. An electron discharge device having an envelope containing a straight thermionic cathode and a plurality of anodes surrounding said cathode, and a collecting electrode outside of said anodes for receiving electrons from said cathode, and means for inducing a magnetic field between said cathode and anodes parallel to said cathode, said collecting electrode being subdivided into sections at right angles to the axis of the cathode and electrically insulated from each other.

KARL FRITZ.
